(57) **CLAIM**

I claim the ornamental design for the collapsible storage bowl, as shown and described.

DESCRIPTION

FIG. 1 is a top perspective view of the collapsible storage bowl, showing my new design.

FIG. 2 is a front view of the collapsible storage bowl, the back, left side, and right side views being identical.

FIG. 3 is a top view of the collapsible storage bowl; and, FIG. 4 is a bottom view of the collapsible storage bowl.

The broken lines in the drawings depict environmental subject matter and form no part of the claimed design.
